LOOSE LEAF BINDER

Filed June 20, 1932

FIG. 1

INVENTOR.

HENRY R. McCLEARY

BY
Benjamin Schlosser
ATTORNEY.

UNITED STATES PATENT OFFICE

1,999,734

LOOSE LEAF BINDER

Henry R. McCleary, Oak Park, Ill., assignor to
 Wilson-Jones Company, Chicago, Ill., a corporation of Massachusetts

Application June 20, 1932, Serial No. 618,167

15 Claims. (Cl. 129—13)

This invention relates to a loose leaf binder and more particularly to a binder of the compression type having covers which may be adjusted to accommodate different thicknesses of sheets.

It is an object of this invention to provide a loose leaf binder having a pair of separable back sections that may be easily aligned and compressed to fit the contents of the binder. It is a further object of this invention to provide readily releasable means for preventing separation of the back sections of the loose leaf binder. It is a further object of this invention to provide simple and efficient means for uniting the cover sections to the back sections of the binder. It is a further object of this invention to provide means for so mounting the sheets in a loose leaf binder that the ratio of the usable width of the sheets to the width of the binder is greatly increased. Other objects of this invention will become apparent upon reading the following description taken in conjunction with the accompanying drawing in which

Figure 1 is a perspective view of the binder with parts broken away to facilitate illustration of the structure;

Figure 2 is a fragmentary detail, partly in section, illustrating the locking structure;

Figure 3 is a fragmentary detail illustrating a modification; and

Figure 4 is a perspective view illustrating a modified pawl releasing means.

In the drawing the reference numerals 2 and 3 designate a pair of complementary metal sections that constitute the back of the binder. The section 2 has its outer edge bent upwardly to form a side wall 4. The edge portion is then bent back upon itself, as indicated at 5, to form a recess 6 in which one edge of a cover member 7 is clinched. The other cover member 8 is similarly secured to the outer edge of the section 3. This method of securing the covers to the back sections greatly simplifies the manufacture of the binders in that it eliminates the necessity of using any adhesives.

The side walls 4 have integral tabs 9 bent therefrom to form prongs upon which a plurality of loose sheets 10 may be impaled. Although the prongs 9 are shown flat, it is obvious that they may be bent to form round posts if desired. The prongs are bent flush with the top of the side walls 4. This construction is particularly advantageous in that it allows the sheets 10 to lie substantially flat so that a minimum of space is wasted at the inner margin. Other binders

having prongs below the top of the side wall must allow additional space where the sheets are bent up over the top of the side wall. If desired, the prongs 9 may be formed separately and then secured to the back sections by welding or riveting.

Each end of the back section 2 is provided with a ratchet 11. As shown in the drawing, the ratchet is formed by cutting through the metal and bending small tabs out of the plane of the section 2. However, the ratchet may be formed in a number of ways, as by crimping or embossing the metal, but cutting out small portions of the metal to form a plurality of apertures, or by welding or riveting a separately formed strip of suitably shaped metal to the section 2. If desired, the section 2 may be formed with a saw tooth end to serve as a ratchet.

The section 3 has an integral member 12 bent back at each end of the section to form a pair of channels 13 in which the ends of the section 2 are adapted to slide. The member 12 extends far enough to cover the entire width of the ratchet 11. A spring pawl 14 is positioned directly over the member 12. One end of the pawl 14 is clinched between the side wall 4 and an integral tab 15 bent back against the side wall inside the recess 6. The top of the side wall 4 is split longitudinally for a short distance, as indicated at 16, to facilitate positioning of the pawl 14 and the tab 15. The cover 8 positioned between the member 5 and the tab 15 serves as a resilient backing for the tab 15 and strengthens the clinching action of the tab 15 and the side wall 4 on the pawl 14. The pawl 14 can be secured to the back section 3 by welding, riveting or soldering, but the method described above is preferable because of its simplicity, efficiency and economy.

The free end of the pawl 14 is curved downwardly, as indicated at 14'. The pawl 14 is slightly longer than the member 12 so that the end 14' projects beyond the member 12 a distance just sufficient to allow it to engage the ratchet 11. The pawl 14 is so shaped that its body is substantially parallel to and adjacent the top surface of the member 12 for a considerable portion of its length when the end 14' of the pawl is in engagement with the ratchet 11.

A metal strap or ring 17 is slidably mounted on the pawl 14. When the ring 17 is moved toward the end 14' of the pawl 14 it contacts with the upper surface of the member 12 and forces the pawl upwardly out of engagement with the ratchet 11. The back sections 2 and 3 may then be moved in either direction. When the ring 17 is moved away from the end 14' the spring action

of the pawl moves the end 14' into engagement with the ratchet 11 so as to prevent outward movement of the back sections. The ring 17 is provided with a roughened surface 18 at its top 5 to facilitate manual operation of the ring. A suitable lug or flange may be provided on the ring instead of the roughened surface.

The modification shown in Figure 3 is the same as the binder shown in Figures 1 and 2 except 10 that one back section 19 is provided with a slot 20 and the other back section 21 is provided with a lug 22. The lug 22 fits in the slot 20 to form a hinge connection. This construction is 15 advantageous in preventing complete separation of the back sections and in facilitating alignment of the sections.

In Figure 4 I have shown a rod 23 secured to one back section 24 by means of a pair of straps 25. The rod 23 is provided with a pair of projections 26 adjacent the straps 25 to abut said straps and prevent longitudinal movement of the rod. Another projection 27 on the rod 23 is positioned under each pawl 28. One end of the rod is bent to form a handle 29. The operator 25 may grasp the handle 29 and rotate the rod 23. The projections 27 will simultaneously lift both pawls 28 out of engagement with their respective ratchets 30.

While I have described a preferred embodiment of my invention in great detail, it will be understood that the description thereof is illustrative rather than restrictive and many details may be modified or changed without departing from the spirit or scope of the invention. Accordingly, I do not desire to be restricted to the exact structure described except as limited by the appended claims.

I claim:

1. In a loose leaf binder, a back member having an outer edge flange bent back upon itself to form a channel, and a cover member fitting in said channel and clinched therein by said flange. 40
2. In a loose leaf binder, a back member having an outer edge flange bent back upon itself to clinch a cover member in position, and a prong formed integrally with said back member and adapted to hold a plurality of loose sheets. 45
3. In a loose leaf binder, a back, a pair of double walled side walls extending along the edges 50 of said back, and a plurality of prongs extending from the bight of said side walls transversely of said back at substantially the same height as the height of said side walls, whereby a plurality of leaves mounted on said prongs may lie substantially flat when said binder is opened.

4. In a loose leaf binder, a pair of telescoping back members, a cover member clinched to each of said back members, a ratchet on one of said back members, and a co-operating pawl on the other back member. 60

5. In a loose leaf binder, a pair of back members, each of said members having its outer edge bent into channel shape to receive a cover member, a ratchet on one back member, and a co-operating pawl on the other back member having one end clinched in one channel, a portion of the cover received by said channel serving as a resilient backing to strengthen the clinching action on said pawl. 65

6. In a loose leaf binder, a pair of back members having side walls integral therewith, prongs integral with said back members extending from said side walls, cover members clinched by said 75 side walls, a ratchet on one of said back members,

and a co-operating pawl on the other back member.

7. In a loose leaf binder, a pair of back members, side walls projecting upwardly from said back members, a plurality of projections struck out of one of said back members, a guide channel extending over said projections, a pawl member having one end clinched in the side wall of the other back member and the other end extending beyond said guide channel to engage said projections, a ring slidably mounted on said pawl member and adapted to bear against said guide channel to move said pawl out of engagement with said projections. 10

8. In a loose leaf binder, a back, a pair of side walls having doubled portions extending along the edges of said back, cover members secured to said walls between said doubled portions and swingable on axes below the top of said side walls, and a plurality of prongs extending transversely 20 of said back at substantially the same height as the height of said side walls, whereby a plurality of sheets mounted on said prongs may lie substantially flat when said binder is opened.

9. In a loose leaf binder, a back member, a side 25 wall having doubled portions extending along one edge of said back member, and a cover secured to said side wall between said doubled portions and forming a hinge at the bottom of said side wall. 30

10. In a loose leaf binder, a back member, a side wall having doubled portions extending along one edge of said back member, a flexible cover member clinched between said doubled portions of said side wall and forming a hinge adjacent the bottom of said side wall, and a sheet holding prong member secured to said side wall adjacent its top. 35

11. In a loose leaf binder, a pair of co-operative back members, side walls projecting upwardly from said back members, a plurality of projections struck 40 out of one of said back members, a guide channel extending over said projections, and a pawl member secured to the other back member, said pawl member extending beyond said guide channel to engage said projections to 45 retain said back sections in co-operative relationship.

12. In a loose leaf binder, a pair of back members, side walls projecting upwardly from said back members, a plurality of projections struck 50 out of one of said back members, the other back member being provided with a guide channel extending over said projections, a pawl member secured to said second mentioned back member and positioned over said guide channel, said pawl member having a tooth extending beyond said guide channel to engage said projections, and means operable between said pawl member and said guide channel to move said tooth into and out 55 of engagement with said projections.

13. In a loose leaf binder, a pair of back members, a pair of side walls secured to the outer edges of said back members, a ratchet on one of said back members, and a co-operating pawl having one end clinched between two component parts of 65 the side wall of the other back member.

14. In a loose leaf binder, a pair of back members, a pair of side walls extending along the outer edges of said back members, a plurality of sheet holding prongs secured to said side walls 70 adjacent the top thereof, a plurality of projections struck out of one of said back members, a guide channel extending over said projections, and a pawl member secured to the other back member, said pawl member extending beyond said 75

guide channel to engage said projections to retain said back sections in co-operative relationship.

15. A binder comprising a pair of separate covers, the binding margin of each being folded against the cover proper to form a binding tongue

maintained in hinged relation to the cover along the fold, said tongues being disposed between the covers proper, a sheath enclosing each tongue, and binding means joining said tongues to each other.

HENRY R. McCLEARY.

CERTIFICATE OF CORRECTION.

Patent No. 1,999,734.

April 30, 1935.

HENRY R. McCLEARY.

It is hereby certified that error appears in the printed specification of the above numbered patent requiring correction as follows: Page 1, second column, line 12, for "but" read by; and that the said Letters Patent should be read with this correction therein that the same may conform to the record of the case in the Patent Office.

Signed and sealed this 11th day of June, A. D. 1935.

Leslie Frazer
